(57) CLAIM

The ornamental design for a table lamp, as shown and described.

DESCRIPTION

FIG. 1 is a top plan view of a table lamp showing my design; FIG. 2 is a left side elevational view; the right side elevational view is a mirror image of the left side thereof; FIG. 3 is a front elevational view thereof; FIG. 4 is a rear elevational view thereof; FIG. 5 is a bottom plan view thereof; FIG. 6 is a cross sectional view taken along lines 6—6 of FIG. 3 thereof; and, FIG. 7 is a front perspective view thereof. FIGS. 1-6 are shown without the lamp shade for clarity of illustration.
